FILLING MACHINE WITH CONSTANT
DRAWBACK

Frank J. Cozzoli, Plainfield, N. J.

Application May 4, 1949, Serial No. 91,306

6 Claims. (Cl. 226—108)

1

The present invention relates to dispensing machines and is concerned particularly with a machine for filling ampuls, tubes, vials and like containers with a pharmaceutical preparation, in a dripless manner. The invention has for its main objectives to render available a relatively inexpensive machine embodying a minimum number of parts easy to manufacture, assemble, and to maintain in clean condition, a machine constructed and arranged accurately to measure and dispense predetermined quantities of liquid preparations into small threated containers, a machine that is constructed to employ as part of the measuring and dispensing mechanism, a standard commercial glass syringe, a machine capable of variation not only in the unit dispensed within the range of the particular syringe used, but capable of variation in the number of filling cycles per unit of time, a machine in which the quantity entrained in the measuring unit on the intake stroke is substantially completely expelled therefrom on the discharge stroke at all quantity settings, and a machine in which the formation of a drop of dispensed fluid on the end of the filling needle on completion of the filling cycle is automatically eliminated whereby wetting the sides of slender threated containers on entering or withdrawal of the needle is avoided.

Characterizing features of the invention include a variable-speed variable-throw crank means operatively connected to reciprocate one of the syringe elements, the other of which is mounted for oscillatory movement in a normally fixed adjustable slide block. The syringe mounting means includes also a valve assembly, including two one-way acting valves, herein disclosed as ball check valves, and wherein the syringe cylinder is in fluid communication with a chamber between the valves and the intake and delivery ports are located respectively at the other sides of the valves so that as the syringe is actuated fluid is drawn past one of the valves into the syringe cylinder and subsequently discharged past the other valve to the delivery conduit and filling needle. The valve assembly is further constructed and arranged automatically to effect a limited return flow of fluid through the needle on completion of the delivery stroke to thereby draw back into the needle the final drop of fluid that ordinarily would tend to adhere to the end thereof. By so drawing back the fluid, undesirable wetting of the throat of the container as the needle enters or leaves a container is avoided.

Other objects and advantages will be in part

indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Fig. 1 of the drawings is a side view of a filling machine embodying the invention.

15 Fig. 2 is a front view of the machine.

Fig. 3 is an enlarged vertical sectional view of a preferred form of valve means incorporating an automatic drop eliminator and drawback feature for the machine.

20 With reference more particularly to Figs. 1 and 2 the filling machine disclosed comprises a main frame member 10 that provides a base 11 for a variable-speed geared-reduction motor 12 and guide ways 13 and 14 for an adjustable slide block 15. The slide block 15 provides journaling means for a valve assembly 16 to which the cylinder 18 of a standard syringe is detachably secured. The piston 19 of the syringe is removably attached to a variable-throw rotatable crank means indicated at 20, that is driven by the motor 12. The assembly 16 is provided with an intake port 21, a syringe port 22, and a delivery port 23, the latter port being in communication with a delivery conduit 24 and the filling needle 25. 25 With the several parts assembled as indicated, operation of the motor will revolve the crank means and reciprocate the piston, causing fluid to be drawn into the syringe cylinder via the valve on an intake stroke and discharged through the needle 25 via the valve on a delivery stroke as will be understood.

40 The power source 12 is a commercial variable speed motor equipped with a lead cord, built in speed regulator, control knob 12a, and resistor 45 (not shown) and need not, it is thought, be further described other than to state that the output shaft 12b may be driven at selectively variable rates within a range effective to produce approximately 8 to 53 fills per hour. The motor shaft 12b is adapted to carry and rotate a crank disc 20a in which a radiating T-slot 20b is formed. The T-slot receives an adjustable crank pin 20c, the latter being formed with a T-head adapted to be clamped in the slot in the disc in a selected radial position by means of a clamp screw 20d.

The crank pin 20c is formed with a reduced end portion over which the eye of a syringe adapter stem 26 is slipped when assembling or removing a syringe. The adapter 26 is formed with an externally threaded seat 27 on and about which a syringe clamp collar 28 is threaded. The collar 28 is formed with an inner conical seat adapted to engage behind the head flange of the standard syringe piston for purposes of simultaneously centering and clamping the piston to the seat. When a syringe smaller than the size illustrated herein is to be used, a conical spacer ring (not shown) is employed within the clamp collar 28 to clamp the smaller piston to the adapter seat.

The cylinder of the syringe, which in this instance is the upper member, is detachably connected to the assembly 16 with a conventional syringe lock device 29 or by other readily detachable means.

The valve assembly 16 is provided with a shaft 30 that extends rearwardly through a journal bearing 31 pressed into the slide block 15 and is constrained against withdrawal by a collar 32 that overlaps the end of the journal bearing 31 and a knurled collar screw 33 threading into the shaft 30.

The slide block 15 is provided with parallel guide surfaces 34 which in cooperation with the ways 13, maintains the block properly orientated in any adjusted position on the main frame. A collar screw 35 threaded into the slide block and a collar 36 abutting the rear ways 14, provides convenient means for clamping the slide block in adjusted position. The purpose of the vertically adjustable slide is properly to locate and relate the cylinder of the syringe to the piston regardless of the size thereof or of the stroke imparted by the variable throw crank 20c. If a small syringe is employed, e. g. 5 cc. capacity, its overall length is shorter than a larger capacity syringe, and if it is desired to use only part of the displacement capacity of the small syringe and have the piston reach to the bottom of the cylinder under any stroke setting of the crank, the slide 15 which supports the cylinder of the syringe must be adjusted upwardly or downwardly accordingly.

The structure of the valve assembly and automatic drop eliminator is disclosed more in detail in Fig. 3, in which 16a indicates a one-piece valve body that is securely mounted upon the shaft 30. The body is vertically bored and reamed to provide a series of coaxial chambers 40, 41, 42 and 43 of progressively decreasing diameter toward the bottom. The upper end of the chamber 40 is threaded to receive a knurled collar plug 44 that normally seals the open end thereof. The lower end portion of the chamber 40 is conically formed and leads to the next smaller chamber 41. The lower end portion of chamber 41 is formed with a conical valve seat 41a that leads into the next smaller chamber 42. The lower end of chamber 42 is also formed with a conical valve seat 41a that leads into the next smaller chamber 43, and the latter is in communication with the supply port 21. Ball elements 41b and 42b are contained within the respective chambers 41 and 42 and cooperate with the seats to form one-way opening valves. The valve body is also drilled transversely to provide a delivery port 23 communicating with chamber 40 above the valve therein, and with a port 44 at a point between the two valves so as to place chamber 42 in communication with the syringe port 22. Port 44 is plugged at its outer end, as indicated at 45. The line a

in Fig. 3 indicates the maximum diameter of the ball 41b and which is closely but slidably fitted to the bore 41. When the ball 41b is seated on its conical seat 41a, the side walls of the bore 41 extend a slight distance above or axially beyond the diametral plane a of the ball, and to the extent that the bore extends beyond the diameter of the ball it functions as a cylinder and the ball functions as a piston operable within the cylinder. When the ball 41b is within the cylinder, flow of fluid past the ball in either direction is effectively prevented.

When the piston of the syringe is moving on its intake stroke, a low pressure is created in ports 22, 44 and chamber 42 which causes fluid from the intake line 21 to flow past the ball valve 42b and to enter the syringe cylinder. The upper valve 41, 41a, 41b, remains closed. When the syringe piston moves in its discharging direction, the lower valve 42a, 42b, closes and the ball 41b of the upper valve is lifted off its seat and with a piston-like movement is moved along and out of the cylinder 41 into the larger chamber 40. When that occurs, the pressure fluid passes around the ball and is expelled through the delivery port 23. On the next following intake stroke of the syringe piston, the upper ball 41b, again falls into the cylinder 41 and seals off the flow. However, by reason of the reduced pressure then being created in the chamber between the balls 41b and 42b, the upper ball is drawn further into the cylinder until its movement is stopped by the seat 41a, thereupon the lower ball valve becomes solely effective and fluid from the supply line is drawn into the cylinder.

It will be perceived from the foregoing that as soon as the upper ball 41b, which is in the delivery conduit, reenters the cylinder 41, flow in either direction past the ball is prevented but inasmuch as the ball then acts as a free piston it continues to move toward the abutment 41a creating a low pressure zone above it within the chamber 40. In consequence of this low pressure zone being formed, a portion of the fluid entrained in the delivery conduits 23, 24, and 25 rushes to fill the chamber. Hence any droplet of fluid that would, under other conditions, hang to the needle end on completion of the delivery, is drawn within the needle a limited distance. The extent that the ball 41b is caused to move out of the chamber 40 at the start of the intake stroke determines the extent of draw-back within the needle, the greater the piston-like action of the ball the greater will be the drawback of needle entrained fluid. The preferred practise, however, is to provide a piston-like movement of only the amount necessary to remove the drop at the needle end and to cause a recession of the fluid from the delivery end of the needle a safe distance to prevent air contamination.

During normal operation of the machine the syringe 17 is caused to oscillate by reason of the orbital movement imparted by the crank pin 20c, and this oscillatory motion is transmitted to the valve unit. Because of this rocking motion it has been found desirable to mount the filling needle rigidly and to connect the interior of the needle with the delivery port of the valve by means of a flexible hose connection 24. Figs. 1 and 2 illustrate a preferred needle mount which comprises a support 50 that is carried by the slide 15, and needle adapter 51 detachably secured to the forward end. By removing the needle adapter and providing a longer hose connection 24, the operator may manually position

the needle in filling relation with successive tubes, vials, ampuls, etc. contained for example in a rack or tray without removing the individual container from the rack. The drawback feature herein explained, operates, it will be understood, to eliminate drop formation with either a mobile or fixed needle.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of the United States:

1. A filling machine of the class described comprising in combination an expansible chamber pump mechanism having an inlet conduit and a delivery conduit and one-way acting valve means in each of said conduits, each of said valves comprising a movable valve element and a cooperating valve seat, each operative alternately to open and close as the pump mechanism is actuated whereby liquid is caused to enter the pump mechanism through said intake conduit and thereafter be discharged through said delivery conduit, an open-ended filling needle at the outlet end of said delivery conduit, means operative to vary pump displacement in accordance with the quantity desired to be dispensed by the filling machine on each operating cycle thereof, and means comprising the movable element of the valve means in the said delivery conduit and a portion of the delivery conduit situated on the downstream side of the valve seat responsive to an actuation of the pump mechanism in an intake direction to effect a limited reversal of flow in the said delivery conduit with any given pump displacement setting with a consequent limited pull-back of fluid from the open end of the needle.

2. A filling machine comprising in combination a measuring pump unit, of the expansible chamber character, valve means connected therewith and with a supply conduit and with a discharge conduit, said valve means comprising a body member having a pair of valve seats formed therein, a ball valve element cooperatively related with each of said seats operative alternately to open and close during the actuation of the pump unit, one of said valve elements and its cooperatively related seat being arranged in the pump intake conduit and the other of said valve elements and its cooperating seat being arranged in the pump discharge conduit, an open ended filling needle at the outlet end of said discharge conduit, means operative to vary pump displacement in accordance with the quantity desired to be dispensed by the filling machine on each operating cycle thereof, and means consisting of an element of the valve means in the pump discharge conduit and a coacting cylinder therefor situated beyond the seat for the ball operative on a reduction in pressure effected on an intake stroke of the pump unit to seal the discharge conduit from communication with the pump unit prior to the seat-

ing of the ball on its seat whereby to effect a limited reversal of flow of fluid entrained in the discharge conduit with any given pump displacement setting with a consequent limited pull-back of fluid from the open end of the needle.

3. In combination with a variable delivery filling machine having a piston and cylinder type of measuring unit, valve means therefor, intake and delivery fluid conduits connected with the valve means, an open ended tubular filling needle connected with the delivery conduit and means to actuate the measuring unit and additional means for varying the quantity displaced thereby on each operating cycle, means for effecting a draw-back of a constant volume of fluid medium from the end of the filling needle on each intake stroke of the measuring unit comprising a cylinder element in fluid communication at one end with the cylinder of the measuring unit and in fluid communication at its other end with said delivery conduit, means in said second named cylinder operatively responsive to a positive pressure in said measuring unit to shift said last mentioned means open the said second cylinder to flow therethrough to said delivery conduit, and automatically responsive to a negative pressure in said measuring unit to close the said cylinder to flow therethrough and thereafter to shift in the cylinder a predetermined distance whereby to produce a negative pressure in the delivery conduit and a draw-back of fluid entrained therein and from the open end of the filling needle.

4. In a filling machine embodying a syringe for measuring and dispensing a liquid medium, a filling needle connected therewith and means to actuate the syringe and additional means for varying the unit quantity displaced thereby on each operating cycle, means for effecting a drawback of liquid medium from the end of the filling needle on conclusion of a delivery stroke of the syringe comprising a shiftable piston element movable in an open-ended cylinder formed in the said connection, said cylinder having abutment means at one end thereof adapted to coact with the shiftable piston to limit the movement thereof in one direction and an enlarged chamber at the other end thereof for receiving and containing the piston element when the latter is moved out of its cylinder on a discharge stroke of the syringe whereby to open a flow passageway to the needle, said shiftable element automatically returning into the cylinder and moving into abutting relation with said abutment means on an intake stroke of the syringe whereby the flow passageway is first closed off and the continued movement of the element toward the abutment means effects a drawback of a predetermined quantity of the liquid entrained in the needle.

5. A filling machine of the class described comprising an upstanding support, and auxiliary support adjustably mounted to said upstanding support, liquid measuring and dispensing means comprising a piston and cylinder mechanism and inlet and discharge valve means therefor, means mounted to said main support and connected to actuate said piston and cylinder mechanism to effect pumping action, connections between said piston and cylinder mechanism and said valve means for the passage of liquid and between said valve means and a supply conduit and between said valve means and a delivery conduit, means for varying the stroke of the piston and cylinder mechanism whereby to ef-

fect changes in unit quantity displaced on each operating cycle, means mounting the said valve means and one of the elements of said piston and cylinder mechanism to said auxiliary support, and means for adjusting said auxiliary support on said main support to position the parts carried thereby in operative relation with the movable element of the piston and cylinder mechanism to maintain a given operating relation therewith in all operating strokes, and means in the delivery conduit beyond the zone of normal valving operation of said valve means operative in conjunction with a part of the discharge valve means to close the conduit to liquid flow at the start of an intake cycle of said piston and cylinder mechanism and prior to the actuation of the discharge valve means to normally closed position.

6. A filling machine of the character described comprising in combination a measuring unit including a piston element and a cylinder element, crank means connected to reciprocate the piston of the measuring unit, means to vary the throw of said crank whereby to vary the stroke of said piston, means mounting the cylinder of said measuring unit for adjustment relative to the piston whereby to maintain a substantially constant relation between the piston and cylinder at least in one extreme position of reciprocation of the piston throughout the range of stroke adjustment, valve means for the measuring unit comprising a body member having a stepped bore of progressively differing diameters formed therein, a ball element loosely contained in one of the chambers of the stepped bore and cooperatively related to one end there-

of to form a valve, a second ball element fitted piston-like to another of the chambers in said stepped bore and adapted for movement into a third and larger chamber of said stepped bore, 5 a fluid conduit connecting said bore at a region between the said balls therein with the cylinder of said measuring unit, a fluid intake conduit and a fluid delivery conduit connected with said bore respectively on the other sides of said first and second mentioned balls, said second mentioned ball responding to a positive pressure in the cylinder to move out of its chamber into said larger chamber whereby to permit a flow through the delivery conduit and operatively responsive to a negative pressure in the cylinder 10 to move into its closely fitting chamber and operate as a piston therein whereby to draw back a predetermined quantity of the fluid entrained in the delivery conduit, said draw back of fluid 15 remaining constant in quantity under all stroke settings of measuring unit.
